FLAT FULL-FASHIONED KNITTING
MACHINE

Karl Richard Lieberknecht, Oberlungwitz, Germany, assignor to Kallo, Inc., New York, N. Y., a corporation of New York

Application May 5, 1937, Serial No. 140,849

7 Claims. (CL 66—96)

The present invention relates to flat full-fashioned knitting machines, and more particularly to improvements in mechanism for controlling and shifting the several groups of loop lifting points for producing picot, lacework, clock and similar decorative effects in knitted hosiery.

In the production of design work, and more particularly in the production of symmetrical clock designs, it has been found desirable to provide mechanism for producing simultaneous movements of the lace points forming these clocks in equal and opposite directions. To this end, mechanisms have been provided as, for example, in the patent to Richter No. 2,059,806, dated November 3, 1936, to positively connect the lace point carrier rods through a reversing motion, so that the movement of one lace rod will cause an equal and opposite movement to take place in the operation of the other lace rod.

It is a principal object of the present invention to provide a simplified and improved pattern control mechanism for controlling simultaneously the positions of reversely movable lace rods and points supported thereon for the production of designs, symmetrical with relation to a center line of the fabric, which is simple and sturdy in construction, being wholly supported on the fixed portion of the machine frame, and provides a maximum flexibility of control for the formation of decorative designs.

It is a further object of the invention to so construct and arrange the pattern control mechanism above referred to, as to permit its use for securing decorative effects other than the symmetrical designs above described, and more particularly for the formation of the picot.

With these and other objects in view, as may hereinafter appear, one feature of the invention consists in the provision of an improved lace point pattern control mechanism comprising two slidable control or pusher elements which are supported on the machine frame to engage with and position the respective lace point bars, means for moving said control elements one from the other in opposite directions, and a single pattern control positioning device for imparting the desired positioning movements to the control elements.

Another feature of the invention consists in the provision of a single lace point pattern shift mechanism of this general description having associated therewith two separate pattern chains which may be alternatively rendered operative for the formation of decorative patterns in different portions of the stocking, and are further

constructed and arranged to control for this purpose, different sets of loop lifting points.

The several features of the invention consist also in the devices, combinations and arrangement of parts hereinafter described and claimed, which together with the advantages to be obtained thereby, will be readily understood by one skilled in the art from the following description taken in connection with the accompanying drawings, in which Fig. 1 is a sectional view in left side elevation of a flat full-fashioned knitting machine embodying in a preferred form the features of applicant's invention; Fig. 2 is an enlarged detail view of the transfer points illustrated in Fig. 1, but with the lace points moved out of the way, and the picot point bar in operating position; Fig. 3 is an enlarged front elevation partly in section, of applicant's improved lace mechanism; Fig. 4 is a plan view of substantially the parts shown in Fig. 3; Fig. 5 is a left side elevation of substantially the parts shown in Figs. 3 and 4; Fig. 6 is a sectional detail view taken on the line 6—6 of Fig. 4, illustrating particularly certain portions of the motion reversing mechanism for the lace bar control or pusher elements; Fig. 7 is an enlarged fragmentary plan view of the slidable positioning element and certain of the associated parts shown in Fig. 4; Fig. 8 is a detail view in front elevation partly in section, illustrating particularly the loop transfer shift mechanism, and with the main cam shaft in knitting position; Fig. 9 is a fragmentary detail view illustrating a position of the parts with the cam shaft shifted to narrowing position, and with the loop transfer shift mechanism set to make a left transfer of the lifted loops; Fig. 10 is a detail view similar to Fig. 9, but with the shift mechanism positioned for a right transfer of the lifted loops; Fig. 11 is a somewhat fragmentary view in front elevation illustrating particularly the connections from the main pattern chain of the machine for throwing the lace mechanism into and out of operation; and Fig. 12 illustrates a typical lace design having two clocks symmetrically arranged with relation to the center line of the stocking blank.

The machine disclosed in the drawings as embodying in a preferred form the several features of applicant's invention, comprises a multiple section flat full-fashioned knitting machine which may be of ordinary description comprising a series of transverse frames 20 on which are carried the usual top rail 22, bottom rail 24, back rail 26, and a work supporting table 28. The

machine is also provided with the usual main cam shaft 30 running the length of the machine, together with a number of supporting and operating shafts for various operating machine elements which will be described only as found necessary to illustrate the several features of applicant's invention in connection with this machine.

The knitting instrumentalities associated with each section include a series of needles 32 movable as a unit, individually movable yarn measuring sinkers 34 and knockovers 36 which have the usual construction and mode of operation of these elements in machines of the general type disclosed. The machine is further provided with 15 a narrowing machine which is of ordinary description comprising a number of supporting arms 40 pivotally supported at spaced intervals along the length of the machine on a shaft 42, and rigidly connected at their forward ends by 20 means of a rod 44 to form the narrowing machine frame. The rod 44 has rigidly secured thereto a number of brackets 46 in which the narrowing point rods generally designated at 48 are slidably mounted, and brackets such as those 25 designated at 50 and 52 in Fig. 3, journaled to receive a picot rod 54 and lace point rods 56 and 58. In accordance with the usual practice, a picot bar 60 is provided for each knitting section supported on picot rod 54, together with two 30 lace point units 62 and 64 mounted respectively on the lace rods 56 and 58. As shown in Fig. 1 of the drawings, the lace point units 62 and 64 have been moved downwardly into operating position, and the picot bar 60 has been raised to 35 inoperative position. When it is desired to bring the picot bar 60 into operating position, the lace point units 62 and 64 are raised, and the picot bar 60 swung downwardly into operating position as shown in Fig. 2.

40 In order to control the positions of the picot bars 60 and lace point units 62 and 64 lengthwise of the machine, two control elements in the form of pusher or stop members 66 and 68 are provided, the pusher member 66 being arranged 45 in close proximity to the picot rod 54 and lace point rod 58, for engagement against stop members 70 and 72 secured respectively to these rods, the pusher member 68 being similarly arranged in close proximity to lace rod 56 for engagement 50 against a stop 74 secured to rod 56. Compression spring 76 coiled about rod 54 between the stop 70 and supporting bracket 52, and similarly, a compression spring 78 coiled about rod 58 between the stop 72 and supporting bracket 52, 55 operate to maintain these rods at all times in their extreme position to the left as shown in Fig. 3, against the pusher member 66. A compression spring 80 coiled about rod 56 between the stop 74 and supporting bracket 50 operates 60 to maintain the stop 74 against the pusher 68. The pusher member 66 is secured to a bracket 84 which is in turn rigidly secured to a shaft 86 slidably supported in bearings formed in fixed bearing supports 88 and 89 (see Figs. 4 and 7). 65 In order to provide additional support for the bracket 84, the bracket is sleeved also to slide freely on a parallel shaft 92 which is in turn supported to move axially in bearings formed in the fixed bearing bracket 88, and in an additional bracket 94. The pusher member 68 is similarly supported on a bracket 96 rigidly secured to an axially movable shaft 98 slidably supported in alignment with the shaft 86 in bearings formed in the supports 89 and 94. The bracket 96 has 70 75 formed thereon a forward extension sleeved to

receive the shaft 92 which forms a slide support for the bracket.

It will be noted more particularly from an inspection of Fig. 5, that the pusher members 66 and 68 supported as above described, on a fixed portion of the machine, are so shaped as to permit relative vertical movements of the narrowing machine frame carrying the picot rod 54 and the lace point rods 56 and 58, while at all times maintaining engagement with the stop lugs or 10 collars secured to the respective rods.

In accordance with the present invention, a simplified and improved pattern control mechanism is provided cooperating with the pusher members 66 and 68 above described, which may 15 be rendered operative to impart the desired positioning movements to the picot points 60, or alternatively to impart equal and opposite positioning movements to the lace points for the formation of symmetrical clock or similar lace designs 20 in the fabric.

In the preferred form of the invention shown, the control mechanism referred to, comprises a positioning member or bracket 100 (see Figs. 3, 4, 7 and 8) which is rigidly secured to move with 25 the sliding bar 92, and is provided with four stops 102 arranged for engagement with the steps of four stepped segment pattern levers 104. The stops 102 are slightly offset from one another to provide four sub-divisions of the spacing provided by each of the steps formed in the levers 104. Movements are imparted from the positioning bracket 100 to the pusher members 66 and 68 through connections including a loop transfer shift mechanism which acts during the 30 narrowing operation to shift the pusher members in opposite directions a distance of one needle to effect the transfer of the lifted loops either inwardly or outwardly on the needle series as desired. With the present construction, movements of the positioning bracket 100 are directly 35 transmitted to the supporting bracket 84 for the pusher member 66, which movements are transmitted to effect an equal and opposite movement of the supporting bracket 96 through a reversing motion device (see Fig. 4) comprising two 40 racks 106 and 108 secured respectively to the brackets 84 and 96, and a pinion 110 engaging therewith pivoted on a fixed portion of the machine. A tension spring 112 connected between the bracket 84 and a point on the machine frame, acts to force the bracket 84 always to the left. Similarly, a spring 114 connected between the bracket 96 and a point on the machine frame, tends to force the bracket 96 always to the right, 45 in order to take up any play which may exist in the rack and pinion connection, and to maintain the brackets and pushers supported thereby accurately in operating position.

The position of the bracket 84 is directly controlled from the positioning member 100 through a loop transfer shift mechanism comprising a stepped cam lever 116 pivotally supported on a bracket 118 secured to move with the positioning member 100 on the slide shaft 92, and arranged 50 for engagement with a cam roll 120 on the pusher bracket 84. The springs 112 and 114 operate to maintain the roll 120 at all times in engagement with the cam lever 116, and thereby to cause the pusher brackets 84 and 96 to follow the movements of the positioning member 100. The shift cam lever 116 is maintained in the full line position illustrated in Fig. 8 during the movements of the positioning member 100 as hereinafter described, to bring the pushers 66 and 68 and points 75

controlled thereby, to their adjusted position, and is then moved upwardly to effect a right transfer of the lifted loops, or downwardly to effect a left transfer of the lifted loops through connections which include a link 124 (see Figs. 3, 5 and 8) connected at its upper end to the shift cam lever 116, and at its lower end to the forward end of a horizontally disposed cam lever 126 supported to turn on the pivot shaft 127. The cam lever 126 is provided with a roller 128 shiftably supported on a pivot pin 130. During normal knitting, the roller 128 rides on an idler disk 132, and is arranged upon the shogging of the main cam shaft 30 to the right to narrowing position, to engage alternatively with a cam 134 for effecting a right transfer of the lifted loops, or for engagement with cam 136 for effecting a left transfer of the lifted loops. From an inspection of Figs. 8, 9 and 10, it will readily be seen that the raising of the shift lever 116 under the influence of cam 134, will cause roller 120 on bracket 84 to ride on the stepped portion of the lever 116 to move the bracket 84 and the parts associated therewith relatively to the right. Similarly, a downward movement of the shift lever 116 from the full line position shown in Fig. 8 under the influence of the left transfer cam 136, will cause the roller 120 to ride off the lever 116, causing the bracket 84 and parts associated therewith, to move to the left under the influence of spring 112, a distance of one tooth, when further movement of the bracket 84 is arrested by engagement of a stop screw 138 on the bracket 118.

The pattern mechanism provided for controlling the positioning member 100 to produce the desired design effects in the knitting of the stocking, comprises the four pattern stepped segment levers 104 above mentioned, which are loosely pivoted to turn on a supporting shaft 140 and are constructed and arranged to be acted upon by either of two lace pattern chains 142 or 144, the lace chain 142 being provided to control the operation of the picot bars 60 for the formation of the lace border in the welt, the lace chain 144 being provided for the formation of the symmetrical clock design in the leg portion of the fabric. The pattern chain 142 carries thereon pattern buttons 146 which may be located on the chain to be brought into alignment with any one of four stop screws 148 carried on the upper side of the heel portion of each of the four levers 104, and thereby to position the proper step of the selected lever 104 for engagement with the corresponding stop 102 on the positioning member 100. The pattern chain 144 is similarly provided with pattern buttons 150 which may be of different lengths, and are similarly arranged to be positioned beneath any one of the four stop screws 152 which are mounted on the under side of each of the four levers 104. The pattern chain 142 is mounted on a pattern drum 154, being additionally supported on idling drum 156, roll 158 and takeup roll 160. The pattern chain 144 is mounted on a pattern drum 162, being additionally supported on idler drums 164 and 166, rolls 168 and 170, and takeup roll 172.

In the preferred construction shown, a simplified and improved racking mechanism is provided for imparting step-by-step advancing movements to each of the pattern chains in timed relation to the rotation of the main cam shaft 30 of the machine, which comprises a cam lever 174 having a roller 176 adapted for engagement with either of two cams 178 or 179 on the main cam shaft 30. The lever 174 is pivotally supported at its rear end

on the pivot shaft 127, and at its forward end is connected by a vertically extending link 180 to a pawl lever 182 which carries a pawl 184 for engagement with a ratchet 186 secured to turn with the drum 162. The pawl lever 182 is in turn connected through link 187 to a pawl lever 188 which is mounted co-axially with the drum 154 and carries a pawl 190 for engagement with a ratchet 192 secured to turn with the drum 154. The drums 154 and 162 are rigidly secured respectively to rotatable shafts 193 and 194 which are provided at their forward ends with hand levers 196 and 198 to permit the operator conveniently to racking the chains to starting position. In the operation of the machine, only one of the chains 142 and 144 is in operation at one time, it being necessary for the operator to shift the pawls 190 and 184 alternatively into and out of operative position. At the start of the knitting on a new stocking, the pawl 190 is placed in operation and the pawl 184 is thrown out. After the completion of the welt portion of the stocking including the lace border in the welt, the pawl 190 is disconnected and the pawl 184 is dropped into engagement with the ratchet 186.

Prior to each racking of either of the chains 142 or 144, the positioning member 100 is moved to the right against the pressure of springs 112, 114, and the four pattern levers 104 are raised against the pressure of their springs 199 to permit the positioning of the next pattern button beneath one of the levers 104 through mechanism which comprises a cam lever 200 supported at its rear end on the rock shaft 127, and having a cam roller 202 arranged for engagement with either of two cams 204 or 206 on the main cam shaft 30. At its forward end the cam lever 200 is connected by a link 208 to one arm of the bell-crank 210, the other arm of which carries a roller 212 engaging with a contacting surface 35 formed on the left side of the positioning member 100. These connections operate upon upward movement of the cam lever 200 under the influence of its cam, to move the positioning member 100 to the right out of engagement with the stepped segment portion of the levers 104. The rising movement of the cam lever 200 is rendered operative also to move the levers 104 to a raised position through connections which include a cam lever 214 supported at its forward 40 end on a depending bracket 216 on the machine frame, and provided with a roller 218 which rests against the upper side of the cam lever 200. At its rear end the cam lever 214 is connected to a vertically arranged plunger 220 provided at its upper end with a contacting surface 222 for engagement with the under side of each of the levers 104.

The pattern mechanism above described, operates also to control the position of the shiftable roller 128 associated with the loop transfer cam lever 126, to cause the roller 128 to engage with cam 134 to effect a right transfer of the lifted loops, or alternatively with cam 136 to effect a left transfer of the lifted loops. The mechanism for shifting the roller 128 comprises a shifting fork 223 connected at its lower end to the roller 128, and at its upper end to an axially movable shift rod 224 which is in turn acted upon by a bell-crank lever 225 supported to turn 60 on a fixed pivot 226. One arm of the bell-crank 225 is arranged to engage against a collar 227 on the shift rod 224, the other arm being connected by a link 228 to a pattern lever 229 which is supported on the pivot shaft 140 in parallel 65 70 75

relation to the stepped segment pattern levers 104, and is similarly provided with stops for engagement with pattern buttons on either of the pattern chains 142 or 144. A tension spring 230 attached to the outer end of the pattern lever 229, tends normally to maintain the lever in a low position against the contact surface 222 of plunger 220. The shift rod 224 is normally maintained in a limiting position to the right by means of a tension spring 231 connected between one arm of the bell-crank 225 and a collar 232 on the shift rod 224. Assuming that the lifted loops are to be transferred to the right, the pattern lever 229 is permitted to move to its limiting low position, with the plunger 220, rocking the bell-crank 225, so that the shift rod 224 and roller 128 controlled thereby are shifted to an extreme position to the left into engagement with the right transfer cam 134 as shown in Fig. 10. If, on the other hand, a left transfer of the lifted loops is to be effected, a bump on the active pattern chain 142 or 144, is brought beneath the corresponding stop on the pattern lever 229 to maintain this lever in its raised position, thus preventing the movement of the bell-crank 225, and causing the roller 128 to be aligned with the left transfer cam 136, as shown in Fig. 9.

The operation of the pattern mechanism above described, is controlled automatically from the main pattern chain 233 of the machine through connections which are arranged when rendered operative to lock each of the cam levers in a raised inoperative position out of the path of their respective cams, including cam lever for freeing the stepped segment levers 104, the cam lever 174 for racking the lace pattern chain, and the cam lever 126 for producing a left or right transfer. To this end a laterally extending supporting member 234 is provided having formed thereon lugs for engagement beneath the forwardly extending ends of the cam levers 126, 200 and 174. The supporting member 234 is supported at one end on a depending link 235 and at its other end on a link 236 which is connected to a control rod 238 to an upwardly extending arm of a pattern chain lever 240 associated with the main pattern chain 233 of the machine. A compression spring 242 coiled about the control rod 238 between a collar 244 on the control rod and a stationary bracket 246, tends normally to maintain the control rod and the supporting member 234 controlled thereby in their extreme positions to the left as shown in Fig. 11 beneath the cam levers above described, for operating the lace mechanism.

The operation of the lace mechanism above described, during the knitting of a stocking, may be described briefly as follows:—

Prior to the starting of the machine, each of the lace chains 142 and 144 are brought to their starting position by manual operation of the cranks 196 and 198, and the pawl 190 for racking the picot chain 142 is dropped into operative position. The lace mechanism is then brought into operation automatically by the engagement of a bump on the main pattern chain 233 which operates through the connections above described, to shift the supporting member 234 to the right, thus causing each of the cam levers 174, 200 and 126 associated with the lace pattern mechanism, to be brought into operative relation with their respective cams. As the main cam shaft is now shogged to the right, to bring the narrowing machine into operation in ac-

cordance with the usual practice, the cam roller 176 associated with lever 174 is moved from the idler roll 179 onto the racking cam 178, roller 202 associated with cam lever 200 is moved from its idling disk 206 onto its actuating cam 204, and cam roller 128 is moved to the left from the idling disk 132 onto the left shift cam 136. During the subsequent rotation of the main cam shaft 30, the cam lever 200 is raised, acting through the connections above described, to move the positioning member 100 to the right out of engagement with the stepped levers 104 which are now moved to their fully raised position, as shown in Fig. 3 of the drawings. Finally, the cam lever 174 is raised to effect a racking of the pattern chain 142. Assuming that the pattern chain 142 has been racked into a position in which the picot bar 60 is to effect a transfer of the loops, a bump 146 on chain 142 is brought into alignment with a stop 148 associated with one of the levers 104, which is thus positioned to bring the proper step of the selected lever 104 into engagement with the corresponding stop 102 on the positioning member 100, as this member is again permitted to move to the left under the influence of its spring 112 by the downward movement of cam lever 200. At the same time, the positioning of the pattern shift lever 229 supported with levers 104 on pivot shaft 140, operates to position a roller 128 in alignment with one of the cams 134 or 136 to effect a right or left shift of the picot points and loops supported thereon, as may be desired.

After the completion of the welt portion of the fabric and the formation of the lace border on the welt, the pawl 190 for operating the pattern chain 142, is disconnected, and the pawl 184 for forming the clock design is dropped into operative position. At this time the operator also swings the picot bars 60 upwardly to the inoperative position shown in Fig. 1, and moves the lace point units 62 and 64 downwardly into operative position. When the lace pattern mechanism is again thrown into operation by the engagement of a button on the main pattern chain 233 of the machine with pattern lever 240, the pattern mechanism will operate in the identical manner above described, under the control of the pattern chain 144 to produce simultaneous positioning movements of the lace point bars 56 and 58 in equal and opposite directions, and will then cause the lifted loops to be transferred inwardly or outwardly as desired for the formation of the clock design shown in Fig. 12, in which the two clocks formed are symmetrical with relation to a center line of the stocking blank. The double row of markings may be readily formed in each clock by the well known expedient of two successive narrowing operations with an intervening shift of the lace points 62 and 64 controlled as above described, by the lace point pattern mechanism.

The invention having been described, what is claimed is:

1. In a flat full-fashioned knitting machine having a narrowing machine frame and a plurality of lace point carrier bars supported thereby, the combination of two control elements supported for movement lengthwise on a stationary portion of the machine frame, operating connections between certain of said bars and one of said control elements, and between other of said bars and the second control element for imparting lengthwise positioning movements to said bars, a motion reversing mechanism for moving

5 said control elements one from the other in opposite directions, a single positioning member connected to impart positioning movements to one of said control elements, and a lace pattern mechanism for imparting successive positioning movements to said member.

10 2. In a flat full-fashioned knitting machine having a narrowing machine frame and a plurality of lace point carrier bars supported thereby, the combination of two control elements supported for movement lengthwise on a stationary portion of the machine frame, operating connections between certain of said bars and one of said control elements, and between other of said bars and the second control element for imparting lengthwise positioning movements to said bars, a motion reversing mechanism for moving said control elements one from the other in opposite directions, a single positioning member, 15 connections from said positioning member including a loop transfer shift device for imparting positioning movements to one of said control elements, and a lace pattern mechanism for imparting successive positioning movements to said 20 positioning member.

25 3. In a flat full-fashioned knitting machine having a narrowing machine frame and a plurality of lace point carrier bars supported thereby, the combination of two control elements supported for movement lengthwise of the machine, operating connections between certain of said bars and one of said control elements, and between other of said bars and the second control element for imparting lengthwise positioning movements to said bars, a motion reversing mechanism for moving said control elements one from the other in opposite directions, a single positioning member connected to impart positioning movements to one of said control elements, a lace pattern mechanism for imparting successive positioning movements to said positioning member comprising a plurality of pattern chains, and means for rendering said chains selectively operable to impart positioning movements to said positioning member.

30 4. In a flat full-fashioned knitting machine having a narrowing machine frame and a plurality of lace point carrier bars supported thereby, the combination of two control elements supported for movement lengthwise on a stationary portion of the machine frame, operating connections between certain of said bars and one of said control elements, and between other of said bars and the second control element for imparting lengthwise positioning movements to said bars, a motion reversing mechanism for moving said control elements one from the other in opposite directions, a single positioning member for positioning said control elements and lace 35 points controlled thereby for lifting loops from selected needles, connections from said positioning member including a loop transfer shift device for imparting positioning movements to one of said control elements, and a lace pattern mechanism comprising a plurality of pattern chains, and means for rendering said chains selectively operable to impart positioning movements to said positioning member.

40 5. In a flat full-fashioned knitting machine having a narrowing machine frame and a plurality of lace point carrier bars supported there-

4 by, the combination of two control elements supported for movement lengthwise on a stationary portion of the machine frame, operating connections between certain of said bars and one of said control elements, and between other of said bars and the second control element for imparting lengthwise positioning movements to said bars, a motion reversing mechanism for moving said control elements one from the other in opposite directions, a single positioning member 5 for positioning said control elements and lace points controlled thereby for lifting loops from selected needles, connections from said positioning member including a loop transfer shift device for shifting said control elements to effect a right or left transfer of the lifted loops for imparting positioning movements to one of said control elements, a lace pattern mechanism comprising a plurality of pattern chains, and means for rendering said chains selectively operable to 10 impart positioning movements to said positioning member and to determine the direction of transfer of the lifted loops.

15 6. In a flat full-fashioned knitting machine having a narrowing machine frame and a plurality of lace point carrier bars supported thereby, the combination of two control elements supported for movement lengthwise of the machine, an operating connection between one of two symmetrically operable lace point carrier bars 10 and one of said control elements, and an operating connection between the other of said symmetrically operable lace point carrier bars and the second control element for imparting positioning movements to said bars, and additionally 20 to a picot point carrier bar, a motion reversing mechanism for moving said control elements one from the other in opposite directions, a single positioning member connected to impart positioning movements to one of said control elements, and a pattern mechanism for imparting successive positioning movements to said 25 positioning member comprising a picot pattern chain, a lace point pattern chain, and means for rendering said chains selectively operable to impart positioning movements to said positioning member.

30 7. In a flat full-fashioned knitting machine having a narrowing machine frame and a plurality of lace point carrier bars supported thereby, the combination of two control elements supported for movement lengthwise of the machine, operating connections between certain of said bars and one of said control elements, and between other of said bars and the second control element for imparting lengthwise positioning movements to said bars, a motion reversing mechanism for moving said control elements one from the other in opposite directions, a single positioning member connected to impart positioning movements to one of said control elements, a lace pattern mechanism for imparting successive positioning movements to said positioning member comprising a plurality of stepped segment pattern levers, two pattern chains selectively operable for controlling the positions of said levers, mechanism for racking each of said chains, and means under the control of the operator for connecting said racking mechanism to rack selectively one or the other of said chains.

KARL RICHARD LIEBERKNECHT.
